L. BERG

DRIVING BOX SHOE HANGER

Filed Nov. 10, 1922

FIG. 1.

FIG. 3.

FIG. 2.

Inventor

Linas Berg.

By William J. Jaschinski

Attorney

UNITED STATES PATENT OFFICE.

LINAS BERG, OF COLERAINE, MINNESOTA.

DRIVING-BOX-SHOE HANGER.

Application filed November 10, 1922. Serial No. 600,070.

To all whom it may concern:

Be it known that LINAS BERG, a citizen of the United States, residing at Coleraine, in the county of Itasca and State of Minnesota, has invented certain new and useful Improvements in Driving-Box-Shoe Hangers, of which the following is a specification.

My invention relates to driving box shoe hangers for locomotives and its primary object is to provide a hanger adapted to support the driving box shoe while the latter is being taken out of place for the purpose of repairing the same, or during the locomotive driving mechanism.

15 A further object of the invention is to provide an attachment adapted to support a driving box shoe so that the same can be taken down in order to gain access to the locomotive driving mechanism for the purpose of making repairs.

Another object of the invention is to provide an attachment of this character which can be used on any locomotive to support the driving box shoe temporarily and is 25 such as to hold the driving box shoe in position so that it can be readily arranged in its normal position after the necessary repairs have been made.

With the preceding and other objects and 30 advantages in mind, the invention consists in the novel combination of elements, constructions and arrangement of parts and operations to be hereinafter specifically referred to, claimed and illustrated in the accompanying drawing, wherein

Figure 1 is a fragmentary elevation of a locomotive showing my invention supporting a driving box shoe.

Figure 2 is a perspective of the device, and 40 Figure 3 is an elevation taken at right angle to Fig. 1.

Referring in detail to the drawing wherein corresponding characters of reference denote corresponding parts throughout the several 45 views, the numeral 5 denotes a conventional locomotive while 6 the driving box shoe thereof, the latter being provided with a plurality of vertically alined recesses at opposite sides thereof and indicated at 7.

50 The hanger comprises a length of resilient metal designated at 10 and bent intermediate its ends to provide a U-shaped part 11. The ends of the U-shaped part are bent in lateral

and opposite directions as indicated at 12 and then extended at right angles in parallel 55 relation to provide a pair of resilient clamping arms 13, the latter terminating in inwardly disposed extensions 14.

The manner of using the device is as follows:—The U-shaped part 11 embraces part 60 of the under frame of the locomotive while the resilient arms 13 extend upon opposite sides of the driving box shoe indicated at 6. The extensions 14 are then engaged in a pair of the openings 7 and thus hold the shoe 65 while the driving mechanism, not shown, is taken down.

From the disclosure it will be seen that I have provided a simple and inexpensive device of this character which may be used in 70 connection with any type of locomotive for supporting its driving box shoes while the driving mechanism or shoes are being repaired. Also the device supports the shoe in a plane which is horizontally alined with 75 the driving mechanism so that after the necessary repairs have been made the driving box shoe may be slid horizontally with the device sliding on the under frame until it has been received in its mounting.

80 From the foregoing it will be seen that I have provided a simple, inexpensive and efficient means for carrying out the objects of the invention, and while I have particularly described the means best adapted to 85 perform the functions set forth, various changes in form, proportion and in the minor details of construction may be resorted to without departing from the spirit or sacrificing any of the principles of the invention.

90 What I claim as new and desire to secure by Letters Patent is:—

1. A driving box shoe hanger comprising a resilient U-shaped member adapted to embrace the under frame of a locomotive and having extensions at its ends adapted to be engaged with the driving box shoe.

95 2. A locomotive driving box shoe hanger comprising a resilient U-shaped member 100 adapted to hang upon the under frame of the locomotive, a pair of extensions carried by the ends thereof, a driving box shoe, the latter being provided with alined openings at opposite sides adapted to receive the extensions.

3. A device of the character described comprising a resilient U-shaped member bent laterally at its ends and then extended at right angle in parallel relation to afford
- 5 a pair of resilient gripping arms, inwardly extending extensions carried by the gripping arms and adapted to engage a driving

box shoe to hold the same, the driving box shoe and device being capable of sliding horizontally for the purpose of either removing 10 the shoe or replacing it.

In testimony whereof I affix my signature.

LINAS BERG.
